Primary Examiner — Garth Rademaker*Assistant Examiner* — Melanie Pellegrini(74) Attorney, Agent, or Firm — Ostrolenk Faber LLP(57) CLAIM

I claim the ornamental design for an expandable wire bracelet, as shown and described.

DESCRIPTION

FIG. 1 is a front perspective view of an expandable wire bracelet showing my new design.

FIG. 2 is a top plan view thereof the bottom view being identical;

FIG. 3 is a right side elevational view thereof, with the plate, crown and ring structure in the rear removed for ease of illustration.

FIG. 4 is a left side elevational view thereof, with the plate, crown and ring structure in the rear removed for ease of illustration.

FIG. 5 is a front elevational view thereof; and,

FIG. 6 is a perspective view thereof in an environment of use. The broken lines shown in FIG. 6 represent environmental matter and form no part of the claimed design.
